UNITED STATES PATENT OFFICE.

CHARLES E. FULLAM, OF PHILADELPHIA, PENNSYLVANIA.

COMBINATION COMB AND TOOTHBRUSH.

Application filed February 6, 1922. Serial No. 534,516.

To all whom it may concern:

Be it known that I, CHARLES E. FULLAM, a citizen of the United States, residing at Philadelphia, in the county of Philadelphia and State of Pennsylvania, have invented new and useful Improvements in Combination Combs and Toothbrushes, of which the following is a specification.

This invention relates to toilet requisites, and it has more particular reference to combination tooth brushes and combs, the primary object being to provide an article of the foregoing type which will be found exceptionally useful for the traveling public, that is to say, for individuals, who are constantly changing their stopping places.

Another object of this invention is to provide a combination tooth brush and comb which is of simple construction, strong and durable in character, while of a very efficient nature in operation; the same being so made that its various parts may be folded into a compact form so as to be capable of neat packing and occupying but little space.

A further object of this invention is to provide a device of the foregoing specified character characterized by the fact that both the tooth brush and comb are effectively protected from contamination by dust, dirt or other matter tending to foul the same when the device is not in use.

With the foregoing and other objects in view as will later on become more apparent from the following description, my invention consists in certain novel features of construction, combinations and arrangements of parts hereinafter fully described and more specifically defined by the appended claims.

In the further disclosure of the invention reference is to be had to the accompanying drawings constituting a part of this specification, and in which like characters of reference designate the same or corresponding parts in all the views.

Figure 1—is a partly broken view illustrating one practical embodiment of my invention, the dot-and-dash lines indicating the operative position of the comb when in use, the covers or casings for the tooth brush and comb being removed.

Figure 2—is a similar view to the preceding figure but taken at right angles thereto,

but with the tooth brush and comb covers or casings in place.

Figure 3—is an enlarged detail view of a spacing member and the means for locking the comb when in the inoperative position.

Figure 4—is a perspective view of the cover for the comb when not in use.

Figure 5—is a fragmentary enlarged detail of the end of the comb.

Figure 6—is a perspective view of the cover for the tooth brush end of my device; and,

Figure 7—is a detail perspective view of a locking member hereinafter more fully described.

In accordance with the form of my invention illustrated the numeral 8 designates an ordinary tooth brush, the handle portion 9 whereof is slightly increased in thickness or enlarged, and the same is longitudinally and transversely slotted at 10 to provide a forked housing for a comb 11. This cut out or longitudinal slot 10 has its opposed ends 12, 13 arcuately curved and notched at 14, 15 for purposes later on explained. The comb 11 similarly has its ends arcuately curved at 16, 17 and said comb is pivoted by a pin or rivet 18 so as to be capable of swinging 80 through a semi-circle from the inoperative position—shown by the full lines in Figure 1—within the slot 10 to the dot-and-dash—or operative—position indicated on the same figure. It will of course be clearly understood that the curved ends 16, 17 of the comb 11 and the curved ends 12, 13 of the longitudinal slot 10 are of a radius from the pivot pin or rivet 18 such that the comb 11 may swing freely in and out of said slot 10 as 90 later on fully explained. It is also here desirable to point out that the curved end 13 of the slot 10 is formed in a distance or spacing block 19 inserted between the outer forked ends of the handle portion 9, said block 19 being securely riveted or otherwise appropriately fixed in place—in the drawings I have indicated rivet pins 20 as a convenient means.

The aforesaid comb 11 is provided at its 100 one end with an offset lug or projection 21 that snugly reposes in the aforementioned notch 15 against the action of a flat recoil spring 22 conveniently secured at 23—Fig-

ure 3—in the spacing block 19; and it will be observed from said Figure 3 that this spring 22 has a limited upward movement due to a stop 24. The function and purpose 5 of this recoil spring 22 is to force or move the adjacent end of the comb 11 from out of the longitudinal slot 10 so that the latter may be easily gripped by the thumb and fingers and swung on the pivot pin or rivet 10 18 from the inoperative to the operative position as indicated by the dot-and-dash line position in Figure 1, and as will be readily comprehended by those acquainted with the art to which this invention appertains. It 15 is also to be particularly noted that the above mentioned lug or projection 21 seats in the notch 14 when the comb 11 is in use, thereby serving to maintain said comb 11 in proper alignment when in use.

20 In order to provide a simple and effective means for locking or latching the comb 11 in either the inoperative or operative positions, I preferably employ the means most clearly illustrated in Figures 3 and 7, the 25 same comprising an angularly bent rod or pin 25 that has fitted or securely mounted thereon a rectangular plunger member 26 adapted for sliding movement in the cut away part 27 of the aforesaid spacing block 30 19, a compression spring 28 being interposed between said plunger member 26 and the outer end of the cut away part 27. Thus it will be seen that the rod or pin 25 with its connected or attached plunger member 35 26 is normally forced inwards so that the headed end 29 of said pin or rod 25 abuts the outer end of the handle portion 9, while the inner angularly bent part 30 of the rod or pin is forwardly directed into engagement 40 with the abutting end of the comb 11. In this connection it will be seen that the extreme inner end of the angularly bent part 30 is rounded or pointed at 31 to enter or engage in a hole 32—Figure 5—provided for 45 purpose in the end of the comb 11, whereby said comb is effectively retained within the longitudinal slot 10 when not in use. On the other hand it is also to be particularly noted that the aforesaid angularly bent part 50 30 is adapted to latch at the back of the comb 11 when the same is in use, and due to the engagement of the lug or projection 21 in the notch 14 will effectively prevent the comb from movement on its pivot pin or rivet 18. These features I deem of material importance as by their provision the user is enabled to operate or use the device 55 with the full knowledge that the comb 11 is automatically locked when in either the operative or inoperative positions.

In conjunction with my improved combined tooth brush and comb as just described I provide a cover or a case 33—Figures 2 and 6—for the tooth brush 8 which is made 60 of suitable material to effectively protect

said brush when not in use. This cover or case 33 is closed in at one end 34 and it is of a cross-section to compactly and slidably fit the back 35 and bristles 36 of the brush 8 as will be clearly understood on an examination of the drawings. The open end of the cover or case 33 is fitted with a friction-fit hinged flap 37 which when closed grips beneath the brush back 35 at 38—Figure 2—and thereby prevents its accidental displacement, said hinged flap 37 being provided on its outer face with a nail engageable projection 39 whereby said flap may be released or moved to remove the said case or cover 33. Obviously the hinged flap 37 may be spring 70 influenced as will be clearly understood by those conversant with the art. Similarly there is provided a case or cover 40—Figures 75 2 and 4—for the comb end of the device, said case or cover having its one end closed in at 41 and being of a cross-section to slidably fit over the aforesaid handle portion 9 when the comb 11 is closed therein as hereinbefore explained.

In operating the combination tooth brush 90 and comb and the user desires to clean his or her teeth for example, the hinged flap 37 is outwardly pulled and the case or cover 34 removed so that the brush 8 may be used and manipulated in the ordinary way. 95 Similarly when it is desired to use the comb 11 the cover or case 40 is firstly removed, whereupon the knob or headed end 29 of the rod or pin 25 is outwardly pulled by the finger nails, said movement disconnecting the 100 angularly bent end or part 30 from latching connection in the hole 32 at the end of the comb 11. Instantly upon the release of the aforesaid latching connection the recoil spring 22 will project the adjoining end of 105 the comb 11 above or outside the handle 9 out of the longitudinal slot 10 therein, whereupon said comb can be swung on its pivot 110 18 until the lug or projection 21 thereon engages in the notch 14 when the aforesaid angularly bent end 30 of the spring influenced rod or pin 25 will engage at the back of the comb 11 and maintain same in secure operative position.

From the foregoing it will be clearly apparent that by my invention I have provided an exceptionally neat, sanitary and effective combination tooth brush and comb, the numerous advantages and benefits whereof as a toilet article for use when traveling 115 will be self-apparent without further elucidation or description, while the brush and comb are effectively protected from contamination by dust and the like.

While there has been described and shown 120 one practical embodiment of my invention, the same is not to be conservatively construed as it will be apparent many detail changes or variations may be easily effected without departing from the spirit and scope 125 130

of said invention as more specifically defined by the subjoined claims.

Having described my invention, what I claim as new and desire to secure by Letters

5 Patent is:

1. A combination tooth brush and comb including a tooth brush the handle whereof is longitudinally and transversely slotted, a comb pivotally mounted in said slotted handle, means for limiting the swinging movement of said comb, means for latching said comb within the slotted handle when the device is not in use, means for turning said comb slightly on its pivot so that the back 10 edge thereof is projected at one end from out the slotted handle when the latching means is withdrawn, and means for protecting the tooth brush proper and the comb from contamination when not in use.

20 2. In a device of the character hereinbefore described the combination of a tooth brush the handle whereof is longitudinally and transversely slotted, the ends of said slot being arcuately curved and provided 25 with notched out parts at one side of the handle, a comb housed within the slotted handle and being pivoted therein, said comb having a projection at one end for seating in the notched out parts of the slotted handle 30 to limit the comb's turning movement, means for latching said comb within the slotted handle when the device is not in use, means for turning said comb slightly on its pivot so that the back thereof is projected at one 35 end from out of the slotted handle when the latching means is withdrawn, means for enclosing the tooth brush proper, and means for enclosing the comb, said means being adapted to protect the brush and comb from 40 contamination when not in use.

3. In a device of the character hereinbefore described the combination of a tooth brush the handle whereof is longitudinally and transversely slotted, the ends of said slot being arcuately curved and provided with notched out parts at one side of the handle, a comb housed within the slotted handle and being pivoted therein, said comb having a projection at one end for seating in the 45 notched out parts of the slotted handle to limit the comb's turning movement, an angularly bent rod slidably mounted in the outer end of the brush handle and having its inner end adapted to engage in a recess or hole 50 provided for the purpose in the end of the comb whereby the comb is securely held in either the operative or inoperative position, means normally projecting said angularly bent rod into operative position relative to the comb, a flat recoiled spring mounted in the notched out part at the outer end of the brush handle, 55 said recoiled spring being adapted to engage beneath the aforesaid projection on the end of the comb when the comb is housed within the slotted handle and turn said comb slightly on its pivot so that the back 60 edge thereof is projected at one end from out of the slotted handle when the angularly bent rod is withdrawn, means for protecting the 65 tooth brush proper, and means for enclosing

the tooth brush proper, and means for enclosing the comb, said enclosing means being adapted to protect the brush and comb from contamination when not in use.

4. In a device of the character hereinbefore described the combination of a tooth brush the handle whereof is longitudinally and transversely slotted, the ends of said slot being arcuately curved and provided with notched out parts at one side of the handle, a comb housed within the slotted handle and being pivoted therein, said comb having a projection at one end for seating in the notched out parts of the slotted handle to limit the comb's turning movement, an angularly bent rod slidably mounted in the outer end of the brush handle and having its inner end adapted to engage in a recess or hole provided for the purpose in the end of the comb whereby the comb is securely held in either the operative or inoperative position, means normally projecting said angularly bent rod into operative position relative to the comb, a flat recoiled spring mounted in the notched out part at the outer end of the brush handle, 70 said recoiled spring being adapted to engage beneath the aforesaid projection on the end of the comb when the comb is housed within the slotted handle and turn said comb slightly on its pivot so that the adjoining back edge thereof is projected out of the slotted handle when the angularly bent rod latching means is withdrawn, means for enclosing the tooth brush proper, and means for enclosing the comb, said enclosing means being adapted to protect the brush and comb from contamination when not in use.

5. In a device of the character hereinbefore described the combination of a tooth brush the handle whereof is longitudinally and transversely slotted, the ends of said slot being arcuately curved and provided with notched out parts at one side of the handle, a comb housed within the slotted handle and being pivoted therein, said comb having a projection at one end for seating in the notched out parts of the slotted handle to limit the comb's turning movement, an angularly bent rod slidably mounted in the outer end of the brush handle and having its inner end adapted to engage in a recess or hole provided for the purpose in the end of the comb whereby the comb is securely held in either the operative or inoperative position, means normally projecting said angularly bent rod into operative position relative to the comb, a flat recoiled spring mounted in the notched out part at the outer end of the brush handle, 105 said recoiled spring being adapted to engage beneath the aforesaid projection on the end of the comb when the comb is housed within the slotted handle and turn said comb slightly on its pivot so that the adjoining back edge thereof is projected out of the slotted handle when the angularly bent rod latching means is withdrawn, means for enclosing the tooth brush proper, and means for enclosing the comb, said enclosing means being adapted to protect the brush and comb from contamination when not in use.

joining back edge thereof is projected out of the slotted handle when the angularly bent rod latching means is withdrawn, a box-like case for slippage over the tooth brush proper, said box-like case having a friction-fit hinged flap adapted to lock beneath the back of the brush and thereby enclose the bristles, and a friction-fit casing

for placement over the handle portion of the device whereby the comb is completely enclosed, said casings being adapted to protect the brush and comb from contamination when the device is not in use.

In testimony whereof I affix my signature.

CHARLES E. FULLAM.
